UNITED STATES PATENT OFFICE.

ASBJORN SONSTHAGEN, OF ESSEX, AND EDMUND HENRY HARBERD, OF LONDON,
ENGLAND.

METHOD AND MEANS FOR ATOMIZING MORE OR LESS VISCID MATERIALS.

1,427,559.

Specification of Letters Patent. Patented Aug. 29, 1922.

Application filed March 25, 1920. Serial No. 368,738.

To all whom it may concern:

Be it known that we, ASBJORN SONS-
THAGEN, a subject of the King of Norway,
residing in Essex, and EDMUND HENRY
5 HARBERD, a subject of the King of Great
Britain, residing in London, England, have
invented certain new and useful Improvements
in Methods and Means for Atomizing
More or Less Viscid Materials, for which
10 we have filed an application in Great Brit-
ain, No. 3364, February 11, 1919, of which
the following is a specification.

This invention relates to a method and
means for atomizing more or less viscid
15 materials, and it has for its object the treat-
ment of viscid materials with a view to
rapidly bringing them to a finely divided
condition.

According to this invention the material
20 is first brought to a condition of a thin
layer or film, and whilst in this state the
said material is transferred to a rapidly
moving body the receiving surface of which
comprises a number of small points from
25 which points the material is flung under
the influence of centrifugal force so that
it is brought to a finely divided state.

The rapidly moving body, which in one
form may comprise a rotary brush, is caused
30 to act upon a film of the material without
actual contact with the drum, roller or
other body carrying said film. By this
means not only is it possible to produce a
more constant effect so far as the fineness
35 of the spray produced is concerned but wear
of the brush through contact with the drum
or roller is avoided.

In practice the material, a syrup for ex-
ample, is first spread uniformly in the state
40 of a thin layer or film by any suit-
able known means upon the surface of a
moving body such as a rotating cylinder,
band or the like. Arranged closely
adjacent to the said cylinder, band or the
45 like is a rapidly moving body which may
conveniently be in the form of a drum or
roller and which body has formed upon it
a number of sharply pointed teeth or pro-
jections, the positioning of the said roller
50 being such that whilst the aforesaid points
will pick up the material they do not con-
tact with the drum from which the material
is being removed. The body just referred
to is caused to move at a high speed when
55 the material picked up by the teeth or pro-
jections is flung from the said points by

centrifugal force being collected in a finely
divided condition. In the arrangement just
referred to it is assumed that the direction
of movement of the adjacent surfaces of the 60
two bodies is the same. It may be found,
however, with some materials that there is
a tendency for the material or a certain
amount thereof to be carried around by the
first roller in which case a scraper is pro- 65
vided whereby the material is removed from
the first roller and taken from said scraper
by the toothed roller which may then be
running in the opposite direction. Such ar- 70
rangement may also be necessary when for
instance the material is of a coarse nature
in order to prevent the toothed roller from
acting as a crushing roller against the film
roller. Instead of a toothed roller a brush 75
may be employed, and if desired provision
may be made whereby prior to contacting
with the material the bristles, by which
term it is intended to include wire or other
material, are held back so that they have a 80
sharp flicking movement. Obviously in-
stead of a roller or brush, an endless band
or the like may be employed provided with
the necessary sharp points, or bristles, as
the case may be. In any case the surface 85
at the moment in contact with the film is
of the smallest possible dimensions consis-
tent with its removal of the material.

In order that the invention may be the
better understood drawings are appended
illustrating one form of the invention as 90
applied to a simultaneous atomization of two
viscid liquids and in which:—

Fig. 1 is an elevation of a machine em-
bodying the present invention.

Fig. 2 is an end view.

Fig. 3 is a diagrammatic view showing
more clearly the arrangement of the rollers
and the atomizing brush.

Fig. 4 is a sectional view illustrating a
modification.

Fig. 5 is an end view, and

Fig. 6 a side view showing an alterna-
tive form of body for removing the film
from the drum.

Fig. 7 is a side view, and

Fig. 8 a front view of a built up form of
body for removing the film from the drum.

Fig. 9 is a front view showing a further
modification of a built up form of body for
removing the film from the drum.

Fig. 10 is a front view of a modified
form of the body shown in Fig. 9.

In the example illustrated the invention is shown applied to a so-called chocolate refining machine being employed for atomizing two substances which it is desired to mix with the chocolate as it passes through the said machine.

In the accompanying drawings *a*, *b* indicate side frames adapted to be secured to the frame of the refiner of which only one roller *x* is shown in Fig. 3. Adjustably secured within the frames *a*, *b* are blocks *a*¹, *b*¹ forming bearings for the trunnions of rollers *c*, *d* which rollers are partly contained within the lower ends of hoppers *c*¹, *d*¹ containing for example sugar and honey. The hoppers are supported by lugs attached to the bearings *a*¹, *b*¹ as shown in dotted lines in Fig. 2 the end walls of said hoppers lying outside the ends of the rollers to prevent the escape of the material at these points, as shown more clearly in Fig. 3. The hoppers are so shaped and mounted that the fronts thereof, at the points *y*, *z* form scrapers permitting a thin film of material to be deposited upon the rollers *c*, *d*. *e* indicates a circular brush mounted in bearings formed in the frames *a*, *b*. The rollers *c*, *d* are driven in any suitable manner from a counter-shaft, not shown, whilst the brush *e* is driven directly from an electric motor by a belt running over pulley *e*¹ secured to one end of the spindle of the brush. The rollers *c*, *d* are so adjusted with respect to the brush that the bristles thereof remove the film of material first from roller *d* and project it on to roller *c* when it forms part of the coating upon said roller and from which it is picked up by the brush and projected on to the roller *x* the particles during their passage through the air being broken up or scattered so that the material reaches the said roller *x* in a finely divided condition.

In order to secure the more efficient action of the bristles they may be restrained just prior to their contacting with the film by means of a bar *f* or other obstruction so placed as to hold the bristles back whereby they have a sharp flicking movement as they engage the material.

Obviously the invention is not limited to the application shown and described as it may be employed for various purposes in which it is essential that a material be brought to a finely divided condition. For example an arrangement such as herein described may be employed for coating a surface, or for decorating articles, sweetmeats for example. In this case instead of employing a continuous brush or its equivalent the said brush may be built up of sections suitably spaced apart whereby lines of various colours or materials may be formed upon the sweetmeat or other articles it is desired to decorate.

Instead of a brush the body carrying the

points or surfaces for removing the material from the roller or drum may comprise a number of surfaces arranged on spiral lines. Such an arrangement is shown in Figs. 5 and 6 where *w* indicates a number of projections of triangular form which projections are arranged in continuous spiral lines as shown in Fig. 6 or if desired the lines may be interrupted to produce a series of sharply pointed teeth. Again the body may be built up of a number of thin toothed discs *w*¹ arranged side by side upon a spindle *w*² as shown in Figs. 7 and 8.

Instead of teeth, however, the discs may be simply provided with a knife edge as shown at *x*¹ Fig. 9. Instead of being formed of separate discs a solid roller may be provided with a number of circumferential grooves as shown at *x*² Fig. 10 the collars thus formed being provided with a knife edge.

Claims:

1. Means for atomizing more or less viscid material comprising a plurality of moving surfaces, in the form of rollers, hoppers supplying the material to said rollers, means for forming films of the material on the surfaces of the rollers, a brush moving at a high speed having bristles contacting with the films but not with the rollers to remove said films, and from which bristles the material is projected by centrifugal force and means engaging said bristles prior to their contact with the material whereby a sharp flicking action is imparted to said bristles as they contact with the material.

2. Means for atomizing more or less viscid material comprising a plurality of moving surfaces, in the form of rollers, hoppers supplying the material to said rollers, means for forming films of the material on the surfaces of the rollers, means for adjusting the hoppers towards or away from the rollers, a brush moving at a high speed having bristles contacting with the films but not with the rollers to remove said films, and from which bristles the material is projected by centrifugal force and means engaging said bristles prior to their contact with the material, whereby a sharp flicking action is imparted to said bristles as they contact with the material.

3. Means for atomizing more or less viscid material comprising a plurality of moving surfaces, in the form of rollers, hoppers supplying the material to said rollers, means for forming films of the material on the surfaces of the rollers, a brush moving at a high speed having bristles contacting with the films but not with the rollers to remove said films from which bristles the material is projected by centrifugal force, means engaging said bristles prior to their contact with the material whereby a sharp flicking action is imparted to said bristles as they

contact with the material and means for adjusting the rollers towards or away from the brush.

4. Means for atomizing more or less viscid material comprising a roller, means for forming a film upon said roller, a second roller means for forming a film upon said second roller, a third roller moving at a high speed and removing the film from the first roller and projecting it by centrifugal force on to the second roller, and means for removing the combined film from the second roller.

5. Means for atomizing more or less viscid material comprising a roller means for forming a film upon said roller, a second roller, means for forming a film upon said second roller, a third roller moving at a high speed, removing the film from the first roller said third roller also contacting with said second roller and removing the combined film therefrom.

6. Means for atomizing more or less viscid material comprising a roller means for forming a film upon said roller, a second roller, means for forming a film upon said second roller, a third roller moving at a high speed and removing the film from the first roller, said third roller also contacting with said second roller and removing the combined film therefrom, means for regulating the thickness of the films upon the rollers and for adjusting the third roller with respect to the film carrying rollers.

7. Means for atomizing more or less viscid material comprising a roller, means for forming a film upon said roller, a second roller, means for forming a film upon said second roller, a third roller moving at a high speed, points or teeth upon said third roller for removing the material from the first roller and projecting it onto the material upon the third roller and removing the combined film therefrom.

8. Means for atomizing more or less viscid material comprising a roller, means for forming a film upon said roller, a second roller, means for forming a film upon said second roller, a third roller moving at a high speed, bristles upon said third roller adapted to contact with the film upon the first roller, means for restraining said bristles prior to their contact with the film upon the first roller whereby a sharp flicking action is imparted to said bristles whereby the material is removed from the first roller and projected by centrifugal force as to the third roller, and means for removing the combined film from said second roller.

9. Means for atomizing more or less viscid material comprising a roller, means for forming a film upon said roller, a second roller, means for forming a film upon said second roller, a third roller moving at a

high speed, points upon said third roller for removing the material from the first roller and projecting it on to the second roller, said points also contacting with the material upon the second roller and removing the combined film therefrom, and means for regulating the thickness of the films upon the rollers and for adjusting the film rollers with respect to each other and the film removing roller.

10. Means for atomizing more or less viscid material comprising a roller, means for forming a film upon said roller, a second roller, means for forming a film upon said second roller, a third roller moving at high speed, bristles upon said third roller adapted to contact with the film upon the first roller and project it therefrom on to the second roller, said bristles also contacting with the combined film upon the second roller and removing it therefrom.

11. Means for atomizing more or less viscid material, comprising a roller, means for forming a film upon said roller, a second roller, means for forming a film upon said second roller, a third roller moving at a high speed, bristles upon said third roller adapted to contact with the film upon the first roller, means for restraining the bristles prior to their contact with the film upon the first roller whereby a sharp flicking action is imparted thereto and the material is projected on to the second roller, said bristles also contacting with and removing the combined film upon the second roller, said bristles also contacting with the combined film upon the second roller and removing it therefrom.

12. Means for atomizing more or less viscid material, comprising a roller, means for forming a film upon said roller, a second roller, means for forming a film upon said second roller, a third roller moving at a high speed, bristles upon said third roller adapted to contact with the film upon the first roller, means for restraining the bristles prior to their contact with the film upon the first roller whereby a sharp flicking action is imparted thereto and the material is projected on to the second roller, said bristles also contacting with and removing the combined film upon the second roller, and means for regulating the thickness of the film upon the rollers and for adjusting the third roller with respect to the film carrying rollers.

In witness whereof we have hereunto set our hands in the presence of two witnesses.

ASBJORN SONSTHAGEN.
EDMUND HENRY HARBERD.
